UNITED STATES PATENT OFFICE.

CHARLES F. CLAWSON, OF MOUNT PLEASANT, IOWA, ASSIGNOR OF ONE-FOURTH TO ADAM WEIR AND ONE-FOURTH TO JOHN T. CORCORAN, BOTH OF MOUNT PLEASANT, IOWA.

RAIL-CLIP.

No. 852,927.

Specification of Letters Patent.

Patented May 7, 1907.

Application filed October 26, 1906. Serial No. 340,701.

To all whom it may concern:

Be it known that I, CHARLES F. CLAWSON, a citizen of the United States, residing at Mount Pleasant, in the county of Henry and 5 State of Iowa, have invented certain new and useful Improvements in Rail-Clips, of which the following is a specification.

This invention relates to railway track appliances, and more particularly that class of 10 such appliances which are designed to prevent creeping of the rails and preserve a correct relation of the ties to the rails.

More specifically, the invention belongs to 15 that type of such devices wherein the clip is secured to the base of the rail and abuts against the side of the tie.

A difficulty hitherto experienced in the practical use of such devices has been the insecurity and inefficiency of the grip of the 20 clip upon the rail owing to the loosening of the fastening devices from vibration; and, being made in two or more parts requiring accurate adjustment relatively to each other and to the rail and tie, their application has 25 involved considerable time, trouble, and consequent expense.

The main objects of the present invention are to increase the practical efficiency and 30 utility of such devices and at the same time simplify their construction and manipulation as well as reduce their cost; and these objects I accomplish through the provision of 35 the device hereinafter particularly described and claimed, the principal novel feature of which consists of a one-piece integral spring 40 steel clip having a transversely elastic body portion adapted to underlie the rail and abut against the side of the tie and jaws on its opposite sides adapted to engage the rail-base when drawn together by a bolt and nut or similar fastening means.

My invention will be readily understood when considered in connection with the accompanying drawings illustrating practical 45 forms thereof, in which—

Figure 1 is an edge elevational view of the preferred form of the invention, shown as applied to a rail and tie; Fig. 2 is a detached perspective view of the clip shown in Fig. 1; 50 and Fig. 3 is a view similar to Fig. 1 (with the tie omitted) of a modified form of clip also embodying the principle of the invention.

Referring to the drawings, 5 may designate an end portion of a railroad tie, and 6 a standard railroad rail supported thereon. The clip forming the subject-matter of the invention comprises as its principal part or element a transversely elastic member bent to shape from a flat strip of soft steel and having a generally loop-shaped body portion 7 the upper ends of the sides of which are provided with jaws 8 and 9 adapted to engage the rail-base in the manner clearly shown in Fig. 1.

In the form of the invention shown in Figs. 1 and 2 the loop-shaped body portion, which is designed to abut against the side of the tie as shown in Fig. 1, comprises an approximately circular bottom portion 10 and parallel straight sides 11 rising therefrom, which latter have registering holes 12 formed therethrough adapted to receive a fastening bolt 13, this latter being equipped with a washer 14 and a nut 15. The elastic steel member is 75 so made that, when detached, the jaws 8 and 9 are spaced apart sufficiently to enable the device to be slipped up over the rail-base from beneath, and the engagement with the rail-base is effected by drawing the sides together (by turning up the nut 15). As the sides normally tend to spread under the elastic resistance of the device, the bolt and nut are under a constant tension, which prevents the nut from jarring loose. It will be 80 observed as an important feature of this form of the invention that the loop-shaped body portion is eccentric or off-center relatively to the jaws, being nearer the end of the tie than is the center of the rail-base. 85 The result of this construction is that the thrust of the clip against the side of the tie, induced by the creeping action of the rail, tends to give the clip an angular or twisting movement, which obviously increases its 90 holding or gripping effect on the rail-base.

In the form of the invention shown in Fig. 3 the body portion of the clip is substantially W-shaped, as shown, the central upward bend or bow, indicated by 16, being preferably of such height that when the device is tightened up into clamping engagement with the rail-base by its bolt 17, washer 18, and nut 19, the bend or bow 16 will contact the bolt and tend to spread the sides slightly, this 100 feature contributing to the rigidity and hold- 105

ing power of the device. In this view I have also shown a positive nut lock which may advantageously be employed, the same consisting of a thin apertured metal plate or strip 20 mounted on the bolt between the washer and the nut, the lower end 20^a of which may be bent beneath the washer 18 while its upper end 20^b may be bent down over the nut 19, thus preventing back-turning of the latter. This nut-lock may obviously be applied to the fastening device shown in connection with Fig. 1, if desired.

From the foregoing it will be seen that my invention provides an exceedingly simple, cheap and effective rail-clip, which may easily be applied and removed, and which has a powerful grip on the rail, which is the most important consideration in the efficiency and practical utility of a device of this character.

Other specific forms within the principle of the invention will readily suggest themselves to those skilled in the art upon acquaintance with the invention as herein shown and described; and hence the latter is not limited to the particular embodiments selected for purposes of illustration except to the extent plainly indicated in the appended claims.

I claim:—

1. A rail clip of the class described, comprising an integral bent steel member having apertured sides terminating in jaws adapted to grip the rail base, and a bolt passed

through the apertures of said sides and drawing the latter together, substantially as described.

35

2. A rail clip of the class described, comprising an integral bent steel member having apertured sides, a transversely elastic portion joining the lower ends of said sides, jaws constituting extensions of the upper ends of said sides adapted to grip the rail base, and a bolt passed through said apertured sides and drawing said jaws into gripping engagement with the rail-base, substantially as described.

40

3. A one-piece rail clip bent to shape from a flat strip of soft steel and comprising jaws adapted to grip the rail-base and a transversely contractible body portion adapted to engage the side of a tie, and a bolt passed through the sides of said body portion and contracting the latter, substantially as described.

45

4. A resilient rail anchor comprising jaws, shoulders adjacent said jaws between which and the jaws the side edges of a rail base are adapted to be gripped, an intermediate portion uniting the shoulders and adapted to extend beneath the rail base, and means for drawing said jaws into engagement with the rail base against the resiliency of the anchor.

50
